ABSTRACT: A hoist has a series of spaced guide pulleys that define a helical path for a cable passed over the pulleys. A ram cylinder is equipped with a piston that moves in an axis coaxial with the axis of said helical path, and means are provided so that movement of the piston separates said pulleys to lengthen the helical path so as to move the cable to lift a load. The pulleys and ram are within a casing, and an internal surface of the casing coacts with extensions of the piston to guide and reinforce the piston for movement in the cylinder.

AIR OPERATED HOIST

This invention relates to a hoist, and more particularly a hoist of that class in which a part of a cable is wound over a series of spaced guides such as grooved pulleys, means being provided for moving the pulleys in directions away from one another, the movements of the pulleys naturally lengthening that part of the cable that is applied to the pulleys, and therefore bringing about the lifting of a load that is attached to one end of the cable.

A hoist of the particular class is well shown in the Platz U.S. Pat. No. 2,613,903 issued Oct. 14, 1952, where linearly spaced pulleys are adapted to be moved relatively to one another to bring about lifting movement of a load attached to a hook on one end of a cable applied to the pulleys. The construction of the Platz patent is particularly adapted for use in a balancing hoist. Thus, the maintenance of predetermined air pressure against the piston of the ram that is found in Platz, is adapted to balance the load, once it is elevated, so that a very light pressure on the load in one direction or the other will be effective to move the load. This is all well set forth in the Platz patent and other prior art patents disclosing balancing hoists.

The invention that I have conceived, while also adapted particularly for use in a load-balancing hoist, is also useful in a hoist of the class in which it is merely desired to lift and lower a load and to hold the load in any lifted position.

My invention and its contribution can be best understood after considering what has been done by the prior art. The earlier hoists of this class, of which Platz is an example, generally utilize a piston that is relatively small in diameter as rather considerable throw is necessary to move the guide pulleys to contribute required lift to the load. By requiring a greater volume of air, a larger piston would naturally act too slowly. Also, the pulley arrangement found in the prior art places considerable stress on the cable, since they require the cable to bend through a rather large angle, thereby shortening its life and seriously affecting its reliability. Generally, also, the earlier arrangements require rather considerable head room because of their vertical dimension, and that head room is wasted since the load cannot be lifted any higher than the lowermost portion of the frame of the hoist.

It is obvious further, that the relatively small piston area utilized in the prior art requires high air pressure, if a heavy load is to be lifted. Frequently, such high pressure is not available in an industrial plant.

In my invention, I contribute a rather unique arrangement of spaced pulleys, making possible the elimination of large angle bends in the cable, and therefore contributing long life to the cable that is required in the operation of the hoist.

As a further feature of my invention, I am able to utilize a ram cylinder of relatively large diameter, having a piston of very considerable area. This means naturally, that even a low air pressure will resolve itself into a rather considerable total pressure applied to the piston. The piston of my ram then can act effectively through the cable guide pulleys to apply extremely high pressures to the hoist cable, so as to contribute swift and effective hoisting movement even though the air pressure is relatively low. The need for large area pistons was recognized earlier by the art, as can be seen by a review of a Powell U.S. Pat. No. 3,260,508. However, no practical way of using a large piston in an effective assembly has been contributed until the present time, so far as I know.

As a further feature of my invention, I mount the ram cylinder and piston so that the axis of movement of the ram piston is parallel to the axis of a helical path in which the cable lies, and in which the cable is guided by the several pulleys. It follows therefore, as will appear quite clearly from a viewing of the drawings of my invention, that my hoist requires a minimum of head room, thereby contributing greatly to its effectiveness and versatility.

Of course, as will be emphasized presently, my hoist contributes this feature of low head room without requiring the hoist to be mounted in an offset and unbalanced position. For an understanding of this feature, reference is made to the Platz

U.S. Pat. No. 2,176,979 of Oct. 24, 1939. Thus, there have been developed hoists using movable pulleys while requiring relatively little head room, but such hoists occupy a relatively considerable length of the beam on which they are mounted, and the load is offset a considerable distance relatively to the mounting of the hoist on the beam so as to exert tilting leverage. A considerable tilting leverage, if a relatively heavy load is to be lifted, presents a rather serious problem. In the hoist contributed by me, the mounting is exceedingly simple, and it is practical to support the hoist through means that are substantially in vertical alignment with the load secured to the load end of the cable.

As a still further feature of my invention, the large diameter piston that I use operates through cam mechanism to bring about the movement of the cable guides or pulleys. This cam mechanism contributes great mechanical advantage to the piston of the ram cylinder, and makes possible the application of a high degree of lifting force and consequent swift and effective movement of the load, with a better balancing of the load while utilizing relatively low air pressure exerted against the piston.

As a further feature of my invention I utilize a novel form of piston and cylinder as well as a novel hoist casing for mounting the several parts. Thus, my piston is naturally formed, in accordance with my concept, with surfaces for moving the spaced pulleys. These surfaces extend from a skirt with which the piston is formed, and which travels in the relatively short cylinder that I utilize with my piston of large sections. Because of the short cylinder I use, the guiding of the piston in its movement becomes critical. I have conceived utilizing the casing in which my piston and cylinder are housed, for this purpose. Therefore, I form my piston with arms or the like extending axially therefrom, preferably from points between the surfaces of the piston that actuate the spaced pulleys, and I provide surfaces on the casing of the hoist for coacting with these arms to guide and support the piston.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention.

Referring now to the drawings:

FIG. 1 shows a longitudinal section of a hoist embodying the invention that I have conceived.

FIG. 2 is a view similar to Fig. 1, but showing parts in a load-lifting position.

FIG. 3 shows a section taken along line 3-3 of FIG. 1, with dash and dotted lines added to show a position of the several cable guides when the load is elevated.

FIG. 4 is an end view of the hoist looking in the direction of the arrow 4 in FIG. 1.

FIG. 5 shows a modification of my invention utilizing two pistons that move several groups of cable guide pulleys.

FIG. 6 is a view similar to FIG. 5, but shows the pulleys moved by the pistons into a position corresponding to the lifting of the load.

FIG. 7 is a section along line 7-7 of FIG. 5. Referring now more particularly to the drawings, and especially FIGS. 1 to 4, the casing of my hoist is designated by reference numeral 10. A part 11 is formed on casing 10 as an integral portion thereof, or is welded thereto. Part 11 is supported through a suitable bearing assembly 12 relatively to a plate 13 that is fastened to a trolley beam 14. The trolley beam 14 is in turn mounted through rollers 15 on a support beam 16. Through the particular construction, the hoist casing 10 will rotate relatively to the trolley beam 14, and may move with beam 14 on rollers 15 relatively to the support beam 16. Of course, it will

be appreciated that the casing 10 may be supported in many ways, and conceivably, may be equipped with a hook for suspension from a ceiling as those skilled in the art will fully appreciate.

One end wall 20 of the hoist casing 10 is dished as shown in FIGS. 1 and 2. At 21 there is an opening in wall 20 that is threaded for fitting 22 attached to one end of an airhose 23. Obviously, air may flow under pressure into a ram cylinder pressure chamber P inwardly of wall 20 whenever desired. My invention contributes a novel ram cylinder and a very unusual piston as I have earlier outlined. This piston is shown rather clearly in section in FIGS. 1 and 2, where it is designated by reference numeral 25. It will be seen that piston 25 has an inclined cam surface 26 against which operate a pair of rollers 27 that are rotatably mounted at one end of a pulley mounting member 28.

It will be appreciated, as is apparent from FIG. 3, that there are three of these mounting members 28, and therefore three sets of rollers 27 operating against three surfaces 26 formed on the piston 25. Therefore, the three surfaces 26 of the piston 25 will be spaced 120° from one another, and that is why only one surface 26 is seen in FIGS. 1 and 2. I have purposely eliminated showing in FIGS. 1 and 2 the two additional mounting members 28 that can be seen in FIG. 3, in order to simplify the showing and to emphasize the construction of the piston 25. It will be well to add that I may use four, five or more mounting members 28, and a like number of surfaces 26, altering then the cross section of the casing 10 in a corresponding manner.

It will be noted that the piston 25 has a skirt portion 30 that is circular, and which is formed so as to carry a piston ring 31, or some suitable packing applied against surface 35 of the ram cylinder, that will make it possible for the piston 25 to move effectively upon the admission of air pressure into the chamber P. In order to balance the relatively short piston 25 for effective movement, it is formed with a series of arms 32, only one of which is naturally shown in FIGS. 1 and 2. All three arms 32 are shown clearly in section in FIG. 3. The three arms 32 rest against three surfaces S on the inside surface of casing 10.

It will be seen also that the three arms 32 are spaced circumferentially 120° apart, just as the cam surfaces 26 are spaced 120° apart, and that the arms 32 are positioned angularly between the surfaces 26 so as to better contribute balanced guidance to the piston 25. Actual contact between the arms 32 and the surfaces S is through ball bearing 32a mounted on the arms 32 by suitable means.

In order to make even more clear the relationship of the parts in FIGS. 1 and 2, line x-x has been added to indicate the axis of the ram cylinder. It is clear that the piston 25 has its center on the line x-x, and that x-x is the centerline of the surface 35 of the ram cylinder relatively to which the skirt 30 of the piston 25 and the packing 31 slide under the influence of air pressure in the chamber P. Lines Y and Z have been shown in FIGS. 2 and 3, further to clarify the relation of the surface 35 of the ram cylinder to the casing 10 and the surfaces S that coact with arms 32.

Each of the three mounting members 28 is formed symmetrically so that at its end opposed to that end on which the rollers 27 are mounted, it carries rollers 36 mounted exactly as are the rollers 27. Those rollers 36 coact with three surfaces 37 formed on the inner surface of a cover 38 that is secured to the end of the casing 10 opposite the dished end wall 20 of the casing. The three surfaces 37 are in exact alignment with the surfaces 26 of the piston 25, and coact with the rollers 36 in exactly the same manner that the rollers 27 coact with the surfaces 26 of the piston 25. It is obvious from FIGS. 1 and 2 that endwise movement of the piston 25 from its position of FIG. 1 to its position of FIG. 2 will bring about the camming movement of the particular mounting member 28 shown in FIGS. 1 and 2 from the position of FIG. 1 to the position of FIG. 2.

The movement of the three mounting members 28 is well illustrated also in FIG. 3. There, in full lines, parts of the three

mounting members 28 are shown in the position of FIG. 1. They are shown in dash and dotted lines in the position of FIG. 2.

I shall now describe the detailed construction of one of the mounting members 28, it being understood that the three mounting members are constructed in a similar way and function in exactly the same manner to bring about a movement of the cable. As is evident from FIGS. 1 and 2, each mounting member includes a shaft 40 that extends between two end walls 41 and 42. Also, I show end walls 41, 42 connected by studs 62 and equipped with portions 43 and 44 on which the several rollers 27 and 36 are mounted for rotation. The shaft 40 is preferably held in position on end wall 41 through a threaded construction 45, and mounted on shaft 40 are a series of ball bearings 46, each ball bearing supporting for separate rotation a guide member in the form of a pulley 47. The several pulleys 47 will be maintained against contact from one another by bearings 46 while freely rotatable individually and independently on the said ball bearings 46. Each of the mounting members 28 does, of course, support its own group of the pulleys 47.

The arrangement of the several groups of pulleys on the several shafts 40 carried by the several mounting members 28, is such that the outer guide surfaces of the pulleys will define a helical path for a cable 50 that is applied to the pulleys, with the axis of the helix coinciding with line x-x. As shown best in FIG. 3, one end of this cable is headed at 51, and through a suitable U-shaped yoke 52 is secured by a pin 53 to an integral portion 54 of the casing 10. From its headed end 51, the cable 50 will extend as probably best seen in FIG. 3, to the right-hand lowermost end pulley 47 and then upwardly over the uppermost pulley and then downwardly to the left-hand lowermost pulley 47, and then around the next right-hand pulley and so forth until it has passed over all of the pulleys desired. It then extends downwardly, as shown in dotted lines at 50a, outwardly of the hoist casing through an opening 55 in the casing to a load hook 56.

I believe it will now be apparent that when the piston 25 is moved from its position of FIG. 1 to its position of FIG. 2, the guide pulleys 47 will move in a direction away from the axis of casing 10. Thus, the several groups of pulleys 47 will have relative separating movements from the full line position of FIG. 3 to the dash and dotted line position of FIG. 3. This will naturally increase the length of the helical path defined by the pulleys 47, and will increase the length of the cable occupying that path, thereby bringing about the lifting of the hook 56 and a load attached thereto.

Of course, should balancing control be applied to air pressure acting through hose 23 against the piston 25, the load on hook 56 will be held balanced so that that load may be manipulated as set forth in the prior art patents to which I have referred. However, it will also be appreciated that the hoist that I have described will operate effectively without the balancing feature, merely through the application of pressure to the piston 25, and the holding of the piston 25 under pressure in a particular elevated position of the load. When simply used for lifting purposes, my hoist can operate with considerable speed so as to lift a load swiftly.

In order to hold the cable 50 on the several guide pulleys 47, each of the mounting members 28 is equipped with a cover 60, best shown in FIG. 3, is preferably formed of metal, and has a pair of eyes 61 which are held in place on the end plates 41 and 42 by the studs 62. In order not to complicate the showing, these studs are not illustrated in FIGS. 1 and 2, but are well shown in section in FIG. 3. Of course, those skilled in the art will appreciate the means for effectively holding the cable in position may be otherwise formed, but I prefer the means illustrated.

In FIGS. 5, 6 and 7, I show a modification of my hoist in which there are several mounting members each designated by reference numeral 70. Actually, there are six of the members 70 as will be clear from FIG. 7, certain of the members being omitted for reasons of clarity in FIGS. 5 and 6. There is

a group of individually mounted guide pulleys 71 on each member 70. A cable 72 is mounted in a helical path as determined by the several pulleys 71, the nature of this helical path being indicated in FIGS. 5 and 6. Thus, it will be noted that the extreme left pulley 71 on the bottom mounting member 70 of FIG. 5 is directly under a spacer 73 on the upper mounting member 70. The bottom portion of the hoist casing may have a guide wheel 72a that lies in a plane to the left of the extreme left pulley 71 on upper mounting member 70. The remaining pulleys, including those pulleys of the other mounting members in both modifications of my invention are similarly related and define what I term a helical path.

In the modification of FIGS. 5, 6 and 7, instead of utilizing a single piston, I utilize a pair of pistons, one being designated by reference numeral 74 and the other by reference numeral 75. The two pistons operate in a cylinder 76 formed with a center wall 77 having a passage 78. The piston 75 has a threaded opening 79 to which is secured the end fitting 80 of an airhose 81. It is obvious that when air is admitted into the cylinder 76, it will flow to each side of the central wall 77 through the opening 78, and will bring about movement of the two pistons 74, 75 from the position of FIG. 5 to the position of FIG. 6.

Each one of the six mounting members 70, in the modification of FIGS. 5, 6 and 7, is formed with two cam surfaces, one of which is designated 85 and the other 86. The piston 74 is formed with a series of arms 87 having rollers 88 for cooperation with the several cam surfaces 85. Similarly, the piston 75 is formed with a series of arms 89 having a series of rollers 90 that coat with the cam surfaces 86. Obviously, movement of the two pistons 74, 75 from the position of FIG. 5 to the position of FIG. 6 will bring about the movement of the several mounting members 70 from the position of FIG. 5 to the position of FIG. 6. This will act to lengthen the helical path of cable 72 for bringing about the movement of the cable and the lifting of a load L, FIG. 7, which may be attached by a hook 92 to the cable 72.

I claim:

1. In a hoist of the class described, a load cable, a series of spaced cable guides movably mounted on said hoist and having guide surfaces over which said cable is applied, said guide surfaces defining therebetween a helical path for said cable, a ram cylinder on said hoist positioned with its piston moving in an axis traversing the space defined by said helical path and parallel to the longitudinal axis of said helical path, and means whereby said piston moves at least certain of said guides transversely of the axis of said piston and said helical path to move said guides in directions away from one another whereby to effect a lengthening of said helical path and increased winding of said cable about said guides.

2. In the combination of claim 1, the feature that said cable guides are mounted to rotate in axes that are parallel to the axis of said ram piston.

3. In the combination of claim 2, the feature that said cable guides comprise a series of independently rotating grooved pulleys.

4. In the combination of claim 3, the feature of cam means through which sliding movement of said piston moves said grooved pulleys.

5. In the combination of claim 1, the feature that said ram piston moves in the axis of said helical path, and cam means actuated by said piston for moving said guides radially of said axis.

6. In the combination of claim 1, the feature that there are several groups of cable guides with each group mounted on a mounting member as a unit for movement with said mounting member relatively to other groups of cable guides mounted on other mounting members, and cam means through which said piston moves said mounting members to move said groups of guide members away from one another.

7. In the combination of claim 6, the feature that each of said cable guides is a pulley individually mounted for rotation on one of said mounting members while moving bodily with

said mounting member.

8. In the combination of claim 6, the feature that each of said mounting members is so moved by said piston through cam and roller mechanism.

9. In the combination of claim 1, the feature that a group of said cable guides is mounted on each of a plurality of mounting members, and that the endwise movement of the piston moves said mounting members radially of the axis of said piston.

10. In the combination of claim 9, the feature that each of said mounting members is in the form of a beam having a roller and cam connection at one end with the casing of said hoist and a similar connection at its other end with said piston.

11. In the combination of claim 9, the feature that said ram cylinder and piston are in a casing in which said mounting members are also mounted and that said piston is formed with a cam surface coacting with a part of each of said mounting members, a circular skirt on one end of said piston whereby said piston is movably mounted in said cylinder, a series of arms on said piston extending longitudinally from said skirt outwardly of the ram cylinder, and internal surfaces formed on the casing of said hoist against which said arms ride.

12. In the combination of claim 9, the feature that said piston is formed with a circular skirt slidable in the ram cylinder, and a series of circumferentially angularly spaced cam surfaces, each extending from said skirt angularly toward the axis of the piston, said cam surfaces effecting the movement of the mounting members.

13. In the combination of claim 12, the feature that said ram cylinder and piston are in a casing in which said mounting members are also mounted, and that said piston has a series of arms positioned circumferentially angularly between said cam surfaces and extending outwardly of the ram cylinder to lie against the internal surface of the casing of said hoist for guiding said piston.

14. In the combination of claim 1, the feature that said piston is formed with a circular skirt whereby said piston is mounted in said ram cylinder, and a series of circumferentially angularly spaced cam surfaces each extending from said skirt angularly toward the axis of the piston, said cam surfaces effecting the movements of said guides.

15. In the combination of claim 14, the feature that said ram cylinder and piston together with said guides are within a casing, and that said piston has a series of arms positioned circumferentially angularly between said cam surfaces and extending outwardly of the ram cylinder to lie against the internal surface of the casing of said hoist for guiding said piston.

16. In the combination of claim 1, the feature that one end of said cable is fixed to said hoist while the other end extends from one of said guide surfaces to a load, whereby the lengthening of that portion of the cable in said helical path effects lifting of said cable.

17. In the combination of claim 1, the feature that said ram piston moves within the space outlined by said guide surfaces and effects movement of said guides radially.

18. In the combination of claim 1, the feature that said ram cylinder and guides are within a casing with one end of said cable passing out of said casing for lifting a load, said piston having a skirt whereby it slides in said ram cylinder, the axis of said cylinder and piston being in alignment with the axis of said helical path, a series of circumferentially angularly spaced cam surfaces formed on portions of said piston extending from said skirt for moving said guides as said piston moves axially in said cylinder, a series of arms also circumferentially angularly spaced extending from said skirt and lying outwardly of said cylinder, and portions of said casing for guiding said arms and thereby effectively reinforcing said piston.

19. In the combination of claim 1, the feature that there are two pistons in said ram cylinder sliding in opposed directions, and means whereby each of said pistons acts against mounting members on which said guides are mounted to move said guides.
